UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

ALTERNATING-CURRENT RECTIFIER.

1,275,782.

Specification of Letters Patent. Patented Aug. 13, 1918.

Application filed August 24, 1914. Serial No. 358,190.

To all whom it may concern:

Be it known that I, CHARLES P. STEINMETZ, a citizen of the United States, residing at Schenectady, in the county of Schenectady, State of New York, have invented certain new and useful Improvements in Alternating-Current Rectifiers, of which the following is a specification.

My present invention relates to the rectification of alternating currents, and more especially to the rectification of alternating currents of high potential. The object of my invention is to provide a method of and means for rectifying alternating currents of higher potential than can conveniently be rectified by commercial forms of rectifiers in use at the present time, such, for example, as the mercury arc rectifier.

The phenomenon known as corona which is present in high potential distribution systems has been extensively investigated since systems of this nature have come into extensive use, and as a result of these investigations many of its varying characteristics have been discovered. Among other things, it has been discovered that if a metallic point has a high positive potential impressed thereon, the corona will extend out into the surrounding air for a considerable distance, while if an equal negative potential is applied to the point there will be little or no corona formed. I propose to take advantage of this characteristic of the corona to accomplish the rectification of high potential alternating current.

In carrying my invention into effect, I produce, by means of the alternating current which is to be rectified, a corona discharge from a set of electrodes which are so positioned with respect to an electrode or electrodes connected to the direct current circuit that when any one of the first set of electrodes is positive the corona discharge therefrom will reach and be collected by the electrode connected to the direct current circuit. On the other hand, when any one of the first set of electrodes is negative, the corona discharge therefrom will not extend out far enough to reach the electrode connected to the direct current circuit.

In the accompanying drawing Figure 1 indicates diagrammatically a simple way of carrying my invention into effect and Fig. 2 shows a modification of the arrangement shown in Fig. 1. The high potential cur-

rent to be rectified is derived from the transformer 1, the primary of which may be connected to an alternating current generator 2. The terminals of the secondary of the transformer are connected through resistances 3 to electrodes 4 and 5, which are preferably pointed. The middle point 6 of the secondary of the transformer is preferably grounded. One of the direct current line conductors 7 is also connected to the neutral point thus provided, while the other conductor 8 is connected to a third electrode 9 placed at a suitable distance from the electrodes 4 and 5. This electrode may have any form desired, and may also be pointed. The electrodes are preferably made of some refractory metal, but the operation of the device is entirely independent of the material used for the electrodes or any dissimilarity in their form.

While in Fig. 1 I have indicated only a single set of electrodes, it will be apparent that a plurality of electrodes connected in parallel may equally well be employed, and also that a negative electrode 9 may be employed for each one of the positive electrodes as shown in Fig. 2 in case it is desirable. Current consuming devices 10 may be connected across mains 7 and 8.

The distance between the electrodes 4 and 5 and the electrode 9 must be properly adjusted for the potential derived from the transformer. When it is thus adjusted, and the electrode 4, for example, is positive, the corona therefrom will extend out far enough to reach the electrode 9, and there will be a transfer of energy between the electrodes, without the formation of any dynamic arc across the gap. At the same instant, of course, the electrode 5 is negative, and the corona which extends therefrom will not reach the electrode 9. When the electrode 5 becomes positive, the electrode 4 is negative, and a similar action occurs. As a result there will be a succession of unidirectional impulses of current delivered to the current consuming devices 10.

It will, of course, be understood that the current obtained in this way is not, properly speaking, a continuous current, but consists of a series of current impulses. By the use of suitable arrangements of reactance and capacity to smooth out the irregularities in the wave form, however, a continuous current may be obtained in case it is de-

sired. It will also be apparent that by varying the arrangement of the electrodes the same principle may be applied to the rectification of a polyphase current.

5 What I claim as new and desire to secure by Letters Patent of the United States, is:—

1. The method of rectifying an alternating current which consists in supplying the current to be rectified to suitable electrodes 10 to produce successive corona discharges therefrom, positioning a collector element within striking distance of a positive corona discharge and beyond striking distance of a negative corona discharge, and collecting 15 thereby the positive corona discharges to produce a unidirectional current.

2. The method which consists in applying an alternating current potential to suitable electrodes to produce successive corona dis- 20 charges therefrom and collecting the dis- charges from said electrodes only when the electrodes are positive.

3. The combination in a system for the rectification of alternating currents, of a 25 plurality of stationary electrodes, means for impressing an alternating potential upon said electrodes to produce successive corona discharges therefrom, and one or more stationary electrodes so positioned with respect 30 to the first-named electrodes as to receive only the positive corona discharges.

4. The combination in a system for the rectification of alternating currents, of a 35 high voltage transformer, a source of alternating current connected thereto, electrodes connected to the terminals of the secondary of said transformer, one or more stationary electrodes so positioned with re-

spect to the first-named electrodes as to receive the positive corona discharges there- 40 from, but not the negative, and a pair of conductors one of which is connected to a neutral point in the secondary of the trans- former, and the other of which is connected to the last-named electrode or electrodes. 45

5. The combination in a system for the rectification of alternating currents, of an electrode, means for impressing an alternating potential upon said electrode to produce successive corona discharges therefrom, and 50 a stationary second electrode so placed with respect to the first that it will receive only the positive corona discharges.

6. The combination in a system for recti- 55 fying alternating currents of an electrode, means for producing successive corona dis- charges therefrom, and a stationary second electrode so placed with respect to the first that it will receive corona discharges of one polarity only. 60

7. The combination in a system for the rectification of alternating current, of means 65 for producing successive corona discharges by the current which is to be rectified, and a collector element located within striking dis- tance of the positive corona discharges and beyond striking distance of the negative corona discharges for collecting the positive corona discharges to produce a unidirectional current. 70

In witness whereof I have hereunto set my hand this 21st day of August, 1914.

CHARLES P. STEINMETZ.
